ILLUMINATING GAS AND WATER GAS APPARATUS

Filed July 6, 1921

UNITED STATES PATENT OFFICE.

HEINRICH KOPPERS, OF ESSEN-RUHR, GERMANY, ASSIGNOR TO THE KOPPERS DEVELOPMENT CORPORATION, A CORPORATION OF PENNSYLVANIA.

ILLUMINATING-GAS AND WATER-GAS APPARATUS.

Application filed July 6, 1921, Serial No. 482,807, and in Germany May 13, 1919.

(GRANTED UNDER THE PROVISIONS OF THE ACT OF MARCH 3, 1921, 41 STAT. L., 1313.)

The invention relates to an illuminating and water gas plant wherein the fuel column of the water gas generator is materially enlarged vertically, said plant having improved means for the production of steam, for the conservation of heat and for the operation of the hot blasting, with the objects of increased economy and efficiency in gas production.

10 Inasmuch as by the adoption of the incandescent mantle the illuminating power which previously was always demanded of gas has lost its importance, dilution of illuminating gas (coke oven gas) by water gas has been adopted to an ever increasing extent and the water gas, of course, no longer needs to be carbureted with heavy hydrocarbons. The consequences of the war will have the effect of encouraging the manufacture of a gas of 20 superior heating value, of about 400 to 510 B. t. u. per cubic foot, which is best produced by diluting gas obtained in the extraction of gas from anthracite coal with water gas. The water gas is then used as a 25 so-called blue water gas, if only for the reason that the materials necessary for carburetion have risen very materially in price.

In diluting the illuminating gas from coke ovens by such water gas, the idea has, of course, suggested itself, of using the gas resulting during the hot air blasting of the water gas generator in a profitable manner so as not to lose the sensible and latent heat contained therein. This idea has been found 35 impracticable so far because these hot blast gases were too poor and supplied too irregularly. In generating water gas, the original aim was to produce as far as possible only carbon dioxide gas in the hot air blasting stage and it was from this viewpoint that the water gas generators were built and operated. It is true, that the hot blast gases which resulted, were used to heat a carbureter and superheater for assisting the carbureting of the water gas; this use of the 40 blast gases however, is now eliminated for the reasons mentioned above.

Some of the uses, other than for heating the carbureter and superheater of a water gas set, to which hot blast gases have been practically put heretofore in connection with water gas generators, was for operating gas engines, and the air blast period was extended with due consideration of the gas

engines and the quality and quantity of the 55 hot blast gas thus increased, while on the other hand the useful effect of the coke going into the gas generator for the manufacture of water gas was impaired. For heating illuminating gas ovens, that are not adapted for heating by means of gas producers built as a part of such ovens, the hot blast gas has not been used alone heretofore but only when mixed with a richer gas; neither was there any possibility of using it alone to 60 heat such ovens, since the illuminating gas ovens are still heated to-day by gas producers using coke as a fuel self-contained therein in which the gas is employed with its full body heat. The illuminating gas ovens can use heat only above 1000 degrees centigrade so that in using the lean hot blast gas in the hitherto employed recuperative heating of illuminating gas ovens, the useful effect, with reference to the fuel, would be exceptionally slight.

Normally the water gas is made only from coke, i. e., of coke in large pieces and burnt hard. The hot blast gas resulting in this connection is particularly poor on account of the low combustibility of this grade of coke and in order to provide for air-blast gas rich enough for underfiring coke ovens it has been proposed to employ anthracite instead of coke as the fuel for water gas generators. In this connection the volatile ingredients of the anthracite are to be admixed to the hot blast gas in order to thus create a more suitable gas for the purpose of heating the distilling ovens. The charge of a gas generator with anthracite in contradistinction to coke, however, has again a number of disadvantages as regards the water gas production proper so that there are practical obstacles in the way of this idea.

This invention solves the same problem by improving the heating effect of the hot blast gases in two places at the same time, i. e., first, at the place where these gases are generated and secondly, at the place where they are used: first of all, according to the invention, the still comparatively low height of the charge in the water gas generators is discarded or done away with and a high charging column of the height of 20 to 33 feet is used so that during the air blasting period the utmost production of carbon monoxide instead of carbon dioxide gas is

assured. For that purpose the high charging column of course, must be operated on the one hand by means of an air blast subjected to sufficient pressure, and this blast 5 must also be introduced at a correspondingly high temperature of about 800 to 900 degrees centigrade in order to obtain the necessary temperature. This then, at the same time, results in discharging the ashes in a liquid 10 form, which has also been proposed for water gas generators.

This high charging column blown to incandescence with hot air represents at the same time a regenerator for the water gas 15 stage, since here by introducing the steam in a counter current to the air, preheating of the steam is caused which is necessary for the most effective decomposition of the same into water gas. The hot blast gas obtained, 20 which is rich in carbon monoxide, is then utilized for heating the illuminating gas plant in such a way that the air and gas or one of them is preheated as much as is possible in a heat recovery plant, that is to say, 25 one with regenerators. As has been learned by heating such ovens with lean gas, such as blast furnace gas, it is possible to assure in this manner, that is, by preheating the lean gas by flowing it through regenerators, a 30 heating which is sufficiently high and distinguished above everything else by its uniformity.

In addition, the hot blast gas can be used for heating blast heaters by which the low 35 pressure air for the blasting of the water gas generator is preheated to a sufficient degree. The production and leading off from the generator of the hot blast gas with little sensible heat has the additional advantage of 40 making it possible to carry out its purification prior to use, which in actual practice can only be effected at a low temperature, without undue or excessive heat losses. By means of the extent of the preheating it is 45 also possible to regulate the quantity of the water gas generated.

In Fig. 1 of the drawing a plant corresponding with the invention is shown by a diagrammatic elevation partly in section, 50 and in

Fig. 2 is shown a vertical cross-sectional view thereof taken on the line 2—2 of Fig. 1.

The shaft *a* of the water gas generator proper is charged by means of the charging 55 device *b* with coke in pieces of from 3 to 4 inches average diameter, being kept filled up to a height of from 20 to 33 feet. The highly heated air blast fed through the ring conduit *c* is introduced above the hearth 60 through the tuyeres *d* in order to effect a gradual heating of the coke column upward from below. The operation is so managed that the hot blast gases generated in this connection leave the gas generator through 65 connection *e* at a temperature of about 250

degrees C., that is to say, the hot blast is discontinued when great losses of heat result at the top. During the manufacture of the water gas, with the connection *e* closed, steam is introduced at the top through the 70 conduit *f*, being suitably preheated in the charging column, as it passes therethrough in a direction counter to that of the preceding air hot blast, and is decomposed finally to form water gas. The time of the water 75 gas period is determined in this connection by the carbon dioxide gas content desired in the water gas.

The hot water gas at the bottom of the shaft *a* is discharged through openings *g* 80 into which the pipe nests *h* of sub-boilers are built in, which, through an intermediate ring system *i*, are connected to a common upper boiler *k* which is arranged so high that on the one hand the sub-boilers are 85 always kept under water, while on the other hand however, it is possible to supply steam of sufficient pressure, about one atmosphere above atmospheric, in order to make it possible to introduce the same under its own 90 pressure directly in the shaft *a* by the conduit *f* as already described. In that manner as complete a circulation and conservation of the heat as possible is then also insured in this respect. The partly cooled 95 water gas passes through the ring system *l* to the gas holder *m* in which the illuminating gas proper or coal gas produced in coal distilling chambers such as *n* is added.

The hot air blast gas leaving the shaft *a* 100 through the connection *e* is fed to the regenerative plant, *o*, *p*, of the illuminating gas plant, operated reversibly in the well known manner, by whose aid the air and gas are so highly preheated prior to the 105 combustion in the regenerators 17 and 27 respectively that even with the small heating value of the hot blast gases, which moreover are partly cooled, a sufficient heating of the distilling chambers is effected. The 110 dilution peculiar to the hot blast gases in this connection, owing to their content of nitrogen and possibly carbon dioxide gas, has an advantageous effect in that an exceptionally uniform heating of the distilling 115 chambers, especially if they are made as large dimension chamber ovens, can be brought about. The reason for this is that the flues 3 of the chamber ovens must be heated by flame heat, as distinguished from 120 mere sensible heat of waste gas, throughout their entire height and the nitrogen and the carbon dioxide, being inert, retard combustion of the gases in the heating flues 3 and thus cause lengthening of the flame in the flues 3 so that the walls of the flues 3 will be subjected to flame heating throughout the height of the flues 3, instead of being subjected to flame heating merely in their 125 lower portions.

Another part of the hot air blast gas is branched off through the conduit *u* behind the purifying plant *q* and in front of the compensating gas holder *r*, and serves for alternately heating the air blast heaters or stoves *s* and *t* which are alternately charged with air taken from the blower *v*, this air going back through the conduit *w* to the ring main *c* and thus to the tuyeres *d*. In this manner a sufficient preheating of the low pressure air can be obtained in order to bring the high charge of the shaft to the requisite temperature. If water gas of 315 B. t. u. per cubic foot and coal gas of 506 B. t. u. per cubic foot are produced there is obtained, by mixing the gases to get an upper calorific value of 427 B. t. u. per cubic foot, a condition such that the hot blast gas from the enlarged water gas generator is just sufficient to adequately heat the distilling chambers and the air for the hot blast.

If a very reduced amount of water gas is to be admixed to the coal gas, the gases produced during the hot air blasting of the water gas generator will not be sufficient in quantity in actual practice to carry out the heating. For supplementary purposes special additional gas producers can be put up in which inferior fuels are gasified; in addition, another method commends itself, however, by prolonging the hot air blast period of the operation of the water gas generator beyond the requisite measure for bringing its bed up to incandescence for decomposition of steam, it is of course possible to further produce air blast gas the same as in a normal gas producer in which case merely the discharge temperature would rise. Now, so as not to cause, owing to the sensible heat of this gas produced in excess, a loss in the closed heat cycle of the plant as a whole, it is advisable to withdraw this part of the gases, by means of a reversing apparatus provided behind the steam boilers *h*, i. e., situated in a cold place, not through the connections *e* but through the conduit *l* whereby its sensible heat, at least for the greater part, is rendered useful for the evaporation of water. In this connection of course, a cold blast is used if only gas from air and coke is withdrawn at the bottom at *g*.

What is claimed is—

55. 1. Apparatus for increasing the heat efficiency of a gas plant operating for the manufacture of mixed coal gas and water gas comprising, in combination: a coal gas apparatus having a distilling chamber adapted to be heated by combustion of gas in flame flues alongside said chamber and having regenerators below and parallel therewith for communication with such flame flues; a water gas generator having means for supplying steam thereto for water gas genera-
tion; blast heaters for preheating air for said water gas generator; means for supplying preheated air from said blast heaters to said water gas generator; said water gas generator being adapted to form a gas of low 70 sensible heat and rich in carbon monoxide from said air before said gas leaves said generator; means for conducting such airblast gas to the regenerators and flues of said distillation chamber; whereby said water gas generator and the regenerators for the distilling chamber together treat the air-blast gas from the water gas generator so that such gases may give off sufficiently intense heat to effect distillation within said 75 distilling chamber without requiring mixture with a richer gas.
10. 2. Apparatus for increasing the heat efficiency of a gas plant operating for manufacture of mixed coal gas and water gas 80 comprising, in combination: a coal gas apparatus having a distilling chamber adapted to be heated by combustion of gas in flame flues alongside said chamber and having regenerators below and parallel therewith for 85 communication with such flame flues; a water gas generator of relatively great height; means combined with the lower portion of said water gas generator for generating steam; means for conducting such 90 steam to the upper end of said water gas generator; water gas offtake means for leading off the water gas generated through said means for generating steam; blast heaters 95 connected with the lower part of said water gas generator for supplying preheated air blast thereto; air blast gas offtake means for conducting the air-blast gas from the upper end of said generator; means for conducting 100 a portion of said air-blast gas to said blast heaters; and means for conducting a portion of said air-blast gas to the regenerators and flues of said distillation chamber; whereby said water gas generator and the 105 regenerators for the distilling chamber together treat the air-blast gas from the water gas generator so that such gases may give off sufficiently intense heat to effect distillation within said distilling chamber without requiring mixture with a richer gas.
45. 3. Apparatus for increasing the heat efficiency of a gas plant operating for the manufacture of mixed coal gas and water gas comprising, in combination: a coal gas apparatus having distilling chambers adapted 110 to be heated by combustion of gas in flame flues alongside said chambers and regenerators for communication with such flues; a water gas generator having means for maintaining a high fuel bed therein; means directly combined with said water gas generator for generating steam by the heat of said water gas; water gas offtake means for drawing off water gas through said means 115 for generating steam; means for supplying 120
60. 4. Apparatus for increasing the heat efficiency of a gas plant operating for the manufacture of mixed coal gas and water gas comprising, in combination: a coal gas apparatus having distilling chambers adapted 125 to be heated by combustion of gas in flame flues alongside said chambers and regenerators for communication with such flues; a water gas generator having means for maintaining a high fuel bed therein; means directly combined with said water gas generator for generating steam by the heat of said water gas; water gas offtake means for drawing off water gas through said means for generating steam; means for supplying 130
65. 5. Apparatus for increasing the heat efficiency of a gas plant operating for the manufacture of mixed coal gas and water gas comprising, in combination: a coal gas apparatus having distilling chambers adapted to be heated by combustion of gas in flame flues alongside said chambers and regenerators for communication with such flues; a water gas generator having means for maintaining a high fuel bed therein; means directly combined with said water gas generator for generating steam by the heat of said water gas; water gas offtake means for drawing off water gas through said means for generating steam; means for supplying

said steam from said steam generator means to said water gas generator; blast heaters connected with said water gas generator for supplying blasts of preheated air thereto; 5 air-blast gas offtake means for conducting the rich in monoxide air-blast gas from said water gas generator to the regenerators and flues of said distillation chambers; whereby said water gas generator and the generators 10 for the distilling chambers together treat the air-blast gas from the water gas generator so that such gas may give off sufficiently intense heat to effect distillation within said distilling chambers without requiring mixture with a richer gas.

4. Apparatus for increasing the heat efficiency of a gas plant operating for the manufacture of mixed coal gas and water gas comprising, in combination: a water gas 20 generator having means for maintaining a high fuel column; a coal gas apparatus adapted to be heated by combustion of gas in flame flues alongside a distillation chamber and provided with regenerators for communicating with such flues; blast heaters connected with the bottom part of the water gas generator for supply of preheated air blast thereto; lower and upper boilers, said lower boiler being directly combined with 30 the lower portion of said water gas generator; connections between said lower and said upper boilers for thermosyphonic circulation of hot water maintained under pressure in the lower boiler by counter-pressure of the head of water in said upper boiler; means for supplying steam to the upper part of the generator from said upper boiler; water gas offtake connections for leading water gas from said generator 35 through said lower boiler to generate said steam; means for conducting air-blast gas from the water gas generator to said air-blast heaters; and means for conducting the air-blast gas from the water gas generator 40 to the regenerators and flues of said distillation chamber; whereby said water gas generator and the regenerators for the illuminating gas generator together treat the air-blast from the water gas generator so 45 that such gases may give off sufficiently intense heat to effect distillation within said illuminating gas regenerator without mixture with a richer gas.

5. Apparatus for increasing the heat

efficiency of a gas plant operating for manufacture of mixed coal gas and water gas comprising, in combination: a coal gas apparatus having a distilling chamber adapted to be heated by combustion of gas in flame flues alongside said chamber and having regenerators for communication with such flues; a water gas generator having means for supplying steam thereto for water gas generation; means for air-blasting said water gas generator; said water gas generator being adapted to form a gas of low sensible heat and rich in carbon monoxide from said air blast before said gas leaves said water gas generator; means for conducting such air-blast gas to the regenerators and flues of said distilling chamber; whereby said water gas generator and the regenerators for said distilling chamber together treat the air-blast gas from the water gas generator so that such gases may give off 75 sufficiently intense heat to effect the distillation within said distilling chamber without requiring mixture with a richer gas.

6. Apparatus for increasing the heat efficiency of a gas plant operating for the manufacture of mixed coal gas and water gas comprising, in combination: a coal gas apparatus having a distilling chamber adapted for heating by combustion of gas in flame flues alongside said chamber; regenerators therefor; a water gas generator adapted to form a gas of low sensible heat and rich in carbon monoxide from air blown through a fuel bed therein; means for injecting steam into water gas generator; means for combining gases distilled in said distilling chamber and water gas from said water gas generator; a pair of hot blast stoves connected with said water gas generator; means for conducting an air blast 95 from one of said hot blast stoves to said water gas generator; means for conducting air blast gases from said water gas generator; a line connected with said means and in communication with the other of said hot 100 blast stoves and with said regenerators, to conduct air-blast gas thereto, and with a line that is in communication with a gas holder for storage and withdrawal of surplus air-blast gas, to maintain the supply of air-blast gas under pressure to said regenerators and to said stoves constant.

HEINRICH KOPPERS.
